UNITED STATES PATENT OFFICE.

WILLIAM M. WHITTEN, OF SOUTH BEND, INDIANA.

COVER FOR CATCH-BASINS.

SPECIFICATION forming part of Letters Patent No. 468,714, dated February 9, 1892.

Application filed June 27, 1891. Serial No. 397,700. (No model.)

To all whom it may concern:

Be it known that I, WILLIAM M. WHITTEN, of South Bend, in the county of St. Joseph and State of Indiana, have invented certain new and useful Improvements in Covers for Catch-Basins; and I do hereby declare that the following is a full, clear, and exact description thereof, reference being had to the accompanying drawings, and to the letters of reference marked thereon, which form part of this specification, in which—

Figure 1 is a perspective view of my improved cover for catch-basins of sewers, showing the top raised. Fig. 2 is a plan view thereof. Fig. 15 3 is a front edge view. Fig. 4 is a detail side view of the top detached. Fig. 5 is a plan view showing a modified form of the cover.

This invention is an improvement in covers for the catch-basins of sewers; and its object 20 is to provide a cover which can be easily set over the man-hole flush with the pavement and can be readily opened to clean the basin and fastened when closed; and it consists in the novel construction and combination of 25 parts hereinafter described, and summarized in the claims.

Referring by letters to the drawings, the body of the cover consists of a plane-surfaced metal plate A, approximately U-shaped and 30 having lateral short extensions a a at the extremities of its legs. From this plate, near the inner edge thereof, depends a deep vertical flange B, approximately U-shaped in plan and uniting at its ends with short vertical 35 flanges b, depending from the front outer edges of the legs and extensions a, as shown.

C designates a top fitting between the legs of plate A and having laterally-projecting rounded lugs D D at its inner corners adapted to rest in sinks or notches d d in the adjoining legs of plate A, thereby supporting and hinging the top thereon, and from the rear edge of the top project fingers c c, which underlie the edge of the rear portion of plate 45 A and prevent the top being lifted vertically from the plate unless it is turned up to a nearly vertical position, and the fingers, with lateral ribs on the vertical walls of a, also prevent the front edge of the top dropping down too far. From the front edge of the top 50 depends a vertical flange F, strengthened and stiffened by narrow corner-flanges f f, de-

pending from the sides of the top near the front thereof. Flange F has a large recess or opening g in it, across which extend a number 55 of parallel guard-rods G G, the ends of which are secured to flanges f f, as indicated in the drawings. When the top is down, it can be fastened by bolts H, which are inserted through openings h h' in the adjoining portions of flanges f and B, as indicated in Figs. 2 and 3.

It will be seen that there is practically no bottom to my cover. Thus it can be fitted over any sewer basin or inlet or a variety of 65 sizes of basins without any trouble, as no connection between the cover and basin-pipes is necessary. It can also be adjusted vertically to a level with the pavement.

The cover is supported by top plate A, and 70 flange B serves to prevent the incoming sewerage washing out the earth beneath the plate. The top C can be turned back and with it the connected grate-bars, entirely disclosing the top of basin and thereby facilitating its cleaning, or the top can be lifted entirely off after being turned up to vertical position; but when it is down it cannot be displaced by stepping thereon or by force unless it is broken.

The front of the cover may be made straight, 80 rounded, or of other desired configuration, according to the position where it is to be used.

Having thus described my invention, what I claim is—

1. In a cover for catch-basins, the combination of the horizontal approximately U-shaped metal plate having a vertical depending flange near its inner edge with a top fitted between the legs of the plate and having a loose connection therewith at its inner edge and a depending recessed flange on its front edge, substantially as specified. 85

2. In a cover for catch-basins, the combination of the approximately U-shaped plate having lateral extensions at its ends and a vertical flange extending around and near its inner edge with a top having lugs and fingers on its rear end and a depending recessed flange at its front edge, substantially as set forth. 95

3. In a cover for catch-basins, the combination of an approximately U-shaped plate having lateral extensions at its ends and a vertical depending flange extending around 100

and near its inner edge with a top having lugs and fingers on its rear edge engaging said plate and a depending recessed flange at its front end, the corner flanges at the ends 5 thereof, and the transverse rods attached to said corner flanges, substantially as described.

4. The combination of the plate A, having lateral extensions *a a*, sinks *d d*, and vertical flanges B and *b*, with the top C, having lugs 10 D engaging sinks *d*, fingers *c* on its rear edge,

and depending flanges F *f* at its front edge, substantially as and for the purpose set forth.

In testimony that I claim the foregoing as my own I affix my signature in presence of two witnesses.

WILLIAM M. WHITTEN.
